UNITED STATES PATENT OFFICE.

CHARLES E. WOOLF, OF WYNNEWOOD, PENNSYLVANIA.

GARMENT-FASTENER.

1,126,610.

Specification of Letters Patent.

Patented Jan. 26, 1915.

Application filed March 13, 1914. Serial No. 824,418.

To all whom it may concern:

Be it known that I, CHARLES E. WOOLF, a citizen of the United States, residing at Wynnewood, in the county of Montgomery and State of Pennsylvania, have invented 5 certain new and useful Improvements in Garment-Fasteners, of which the following is a specification.

My invention relates to improvements in 10 garment fasteners and one object of the invention is the provision of a fastener which may be constructed of wire or sheet metal and which can be easily fastened or released, but which can not possibly become accidentally unfastened.

Another object of my invention is the provision of a garment fastener which can be easily applied to the flaps or meeting members of a garment and be of ornamental 20 appearance, which can be instantly fastened and released, which will not disfigure the appearance of the garment but give a smooth and neat appearance to the fastened edges, and which will be capable of production at 25 the right price to make the fastener practical and efficient.

With these objects in view, my invention consists of a garment fastener embodying novel features of construction and combination 30 of parts, substantially as disclosed herein.

Figure 1 is a front elevation of the two portions of a garment equipped with my fastener, showing the fasteners in released 35 or unlocked position. Fig. 2 is a similar view, the fastener being locked or fastened and securing the two portions of the garment together. Fig. 3 is a perspective view of the two similar members which compose 40 the fastener. Fig. 4 is a side view of one of the parts of one of the members. Fig. 5 is a sectional view on the line 5—5 of Fig. 3.

The fastener can be made of wire or sheet metal and may be used as a garment or other 45 fastener, as circumstances require, and for the purpose of illustration is shown as constructed of sheet metal and applied to a garment, and in the drawings the letter A indicates the two portions of the garment to 50 be fastened, the fastener consisting of the pair of plates B, provided with eyes C, for

connecting the fastener to the parts of the garment, and secured together in any manner to make a unitary structure, and said plates are bulged at D, to provide the pockets or seats E, adapted to receive the hooks F at the outer ends of said plates, these hooks being secured in proper relation by means of a rivet or like fastening G.

From this construction it will be noted 60 that the two members comprising the fastening are of similar construction and are secured to the edges of the garment by lacing H, or the like, and are disposed in opposite relation, providing the oppositely 65 disposed hooks F and the similarly disposed pockets E, whereby the hooks by a vertical movement are engaged in the pockets, the hook of one member locking in the pocket of the other or companion member and making 70 a perfect locking connection between said members, retaining the edges of the garment in proper relation under all circumstances and allowing the instant engagement or release of the two members forming the fas- 75 tening.

It is evident that I provide a fastening which can be constructed of wire, sheet metal or other suitable material, which can be readily applied, and will be of ornamental 80 and attractive appearance, which can be instantly fastened or unfastened by a natural vertical or horizontal movement, which will hold the parts in proper relation and cannot possibly work loose or become detached 85 accidentally, and which all things considered will be inexpensive and practical.

I claim:

The garment fastener herein described consisting of the pair of similar members, 90 each having an attaching portion at one end, an intermediate pocket extending transversely from one edge thereof, and a hook member at the other end for interlocking with the pocket of the companion member. 95

In testimony whereof I affix my signature in presence of two witnesses.

CHARLES E. WOOLF.
